UNITED STATES PATENT OFFICE

EARL C. SWANSON, OF BAYPORT, MINNESOTA, ASSIGNOR TO ANDERSEN FRAME CORPORATION, OF BAYPORT, MINNESOTA, A CORPORATION OF WISCONSIN

WINDOW AND DOOR FRAME

Application filed November 15, 1929. Serial No. 407,398.

This invention relates to the manner of mounting a jamb on a sill and is designed as an improvement over U. S. Patent #1,708,599, dated April 9, 1929, issued to 5 Fred C. Andersen, in providing a groove or dado extending outwardly from a point near the inner edge of the sill and adapted to conduct rain or melting snow from said inner edge outwardly away from the window and 10 the wall of the building, provision also being made for conveniently nailing if desired, the depending end of the jamb to the abutting face of the sill.

A further object is to provide an improved 15 means for mounting a jamb on the sill which will make it unnecessary to notch the lower end of the jamb, the transverse recess there- in receiving the end face of the sill and permitting convenient nailing if desired.

20 A further object is to provide the lug or projection of the Andersen patent at the lower end of a jamb of the unnotched type adapted for use in a window frame of the sliding sash construction, the lug forming if 25 preferred, the lower wall of the recess in the jamb and adapted to bear on the under surface of the sill when the sill and jamb are assembled and cooperate with means engag- 30 ing the transverse dado or groove in the sill to hold the jamb in an upright position.

35 A further object is to provide a simple and convenient means for uniting the lower end of a jamb with a sill either in a door frame or a window frame of a casement or sliding sash type.

Other objects of the invention will appear from the following detailed description.

The invention consists generally in various 40 constructions and combinations, all as hereinafter described and particularly pointed out in the claims.

In the accompanying drawings forming a part of this specification

45 Figure 1 is a plan view of a sill embody- ing my invention;

Figure 2 is a perspective view of the same;

Figure 3 is a perspective view of the outer face of the jamb;

Figure 4 is a similar view of the inner 50 face;

Figure 5 is a vertical elevation of the jamb;

Figure 6 is a perspective view of the sill and jambs in their assembled relation;

Figure 7 is a horizontal sectional view 55 through one of the jambs;

Figure 8 is an end view;

Figure 9 is a sectional view on the line 9—9 of Figure 7;

Figure 10 is a perspective view of a modified form of sill adapted particularly for a 60 frame of the sliding sash type;

Figures 11 and 12 are perspective views 65 of the lower portion of a jamb of a sliding sash frame;

Figure 13 is a plan view of the sill shown in Figure 10;

Figure 14 is a perspective view showing 70 the sill and jambs of Figures 10, 11 and 12 in their assembled relation; and

Figure 15 is a sectional view on the line 15—15 of Figure 14.

In the drawings, 2 represents a window sill 75 having the usual shoulders 3 and 4 and the projecting ends or horns 5 forming continuations of the outer or forward portion of the sill. Adjacent these horns, the sill is preferably provided with the usual notches or mortises 6. Across the ends of the sill intersecting the shoulders 3 and 4 and extending entirely 80 through the raised portion 7 of the sill are grooves 8 comparatively narrow, preferably having parallel side walls, and each having a bottom that is flush substantially with the outer, upper surface of the sill. These 85 grooves are preferably near the ends of the raised portion 7 and at their inner ends intersect and pass through the shoulder 4. The side walls of these grooves are also preferably parallel with the end walls 9 of the sill and separated therefrom by the narrow raised portions 10 formed when the grooves are cut through the raised section 7 of the sill. When

the frame is assembled in the window or door opening, the mortises or notches 6 will allow 95 the main portion of the sill to be inserted into the opening while the horns or extensions 5 extend outwardly on each side as usual in window or door frame construction of this type.

11 represents the jambs each having at its 100

lower end a transverse rabbet 12 formed in its inner face and the upper wall of each rabbet has a groove 13 formed therein preferably extending entirely across the jamb to provide a depending tongue or web 14. The groove 13 is of sufficient depth to receive the raised portion 10 on the sill and the tongue 14 is adapted to enter the groove 8 and slide therein until the edge of the jamb contacts with the vertical face of the extension 5. The groove 13 and the cooperating tongue 14 and groove 8 are of such form that they fit snugly together when the jamb is positioned on the end of the sill with the flat face of the rabbet 12 bearing against the corresponding surface 9 of the sill in convenient position for nailing when the sill and jambs are assembled. The grooves 8, as will be noted from the drawing, preferably extend entirely across the raised portion of the sill so that rain or the water from melting snow or ice accumulating on the sill and entering the grooves, will be directed thereby to the outer side of the sill and there will be no possibility of moisture from such source entering the wall of the building or passing to the inner side of the sill. The sill and jambs can be easily and quickly assembled and when the frame is ready to be set, the jambs and sill can be secured together in the usual way with the assurance that all moisture collecting in the joint between the jambs and sills will be directed to the outside.

The foregoing views, sheets 1 and 2, illustrate the application of the invention to a frame of the casement type, where as shown in the figures, the inner face of each jamb has a raised central portion extending down to the sill when the sill and jambs are assembled and the shoulder 4 on the sill extends to the edge of the transverse grooves or dados in the sill. Consequently it is hardly practicable in this construction to provide a lug or wall at the lower end of the jamb as that would render it difficult to assemble the sill and jambs and it is undesirable in a window frame of this type to cut away the rear end of the raised portion in each jamb so that it will clear the shoulder on the sill. Hence in this type of frame I prefer to omit the shoulder or lug at the lower end of the jamb.

Referring now to sheet 3 of the drawing, the sill 2^a has the usual horns 5 and raised portion 7 as described with reference to the previous figures, but the rib 4^a at the inner edge of the sill is preferably cut away to form gains 4^b at each end and the sill is provided with transverse grooves or dados 8^a and I may provide rabbets 8^b at the ends of the sill parallel with the dados 8^a and separated therefrom by the ribs 8^c. The jambs shown in this view of the drawing and adapted to fit the sill as described, are of the sliding sash frame type and designated by reference numeral 15. These jambs have transverse rabbets 16 in their inner faces adjacent the lower

end, the lower walls of the rabbets forming lugs or projections 17. The upper wall of the rabbet in each jamb is provided with a transverse groove 18 formed therein adapted to receive the rib 8^c at the end of the sill and a correspondingly shaped tongue 19 is also formed in the upper wall of the rabbet to enter the groove or dado 8^a in the sill, the dado in the jamb being of sufficient depth so that the wall of the groove 18 may enter the rabbet 8^b in the end of the jamb and be seated snugly therein when the sill and jamb are assembled. When this has been done, the wall or lug 17 will bear on the under surface of the sill and cooperate with the interlocking tongues and grooves in the upper wall of the jamb rabbet and the surface of the sill and hold the jamb firmly in position, at the same time permitting lateral relative movement of the sill and jamb to assemble or separate them, if desired. In this type of frame where the gains 4^b are formed at the ends of the rib 4^a, the jambs and sill can be conveniently assembled by a relative lateral movement and it is entirely practicable to have the lug or shoulder formed on the lower end of each jamb without interfering with the convenient assemblage. Then too, in this type of frame there is no central rib or raised portion on the inner face of each jamb as will be noted from the views.

As shown in Figures 11 and 12 a blind stop 20 is preferably provided on the edge of the jamb with a recess 21 in its lower end forming a continuation of the rabbet in the jamb and also provided with a depending tongue 22 forming a continuation of the tongue 19 of the jamb. On one side of this tongue, the upper wall of the recess in the blind stop has a groove 23 forming a continuation of the groove 18 in the upper wall of the rabbet and on the other side of the tongue 22 a rabbet 24 is formed which receives the inner wall of the groove 8^a in the sill as shown plainly in the assembled view 14.

This form of frame as described, provides a very substantial weatherproof joint between the jamb and the upper surface of the sill. I may, however, prefer the form of sill shown in sheets 1 and 2 herewith, where the transverse rib on the sill is close to the end thereof, without having the rabbet formed between it and the vertical end wall. This construction is adapted for a frame of the sliding sash type as well as a casement frame shown in sheets 1 and 2 but in a sliding sash frame construction it is preferable to provide a rib or shoulder at the lower end of the jamb to bear on the under surface of the sill in the same manner as shown in sheet 3 of the drawing, and as particularly illustrated in Figure 15. The rabbet may be formed in the end of the sill for either the casement or sliding sash type of frame. In some cases this rabbeted sill construction may be preferable to the single transverse groove construction

shown in the casement window figures of the drawing.

When the sill and jambs are assembled, the face of the blind stop will butt against the wall of the horn 5 of the sill and with the construction of either form of sill and jamb, the joint between them will be substantially weatherproof and the extension of the dados in the sill through a substantial portion thereof from the inner edge, will conduct moisture outwardly away from the wall of the building and the inner portion of the window, an important consideration in window frame construction.

I have shown the invention incorporated in a window frame of a casement and sliding sash type but it will be understood that the idea is equally applicable to the frame of a door where it is desirable to conduct moisture away from the walls and the interior of the building.

In various ways the details of construction herein shown and described may be modified and still be within the scope of my invention.

I claim as my invention:

1. A sill having a raised portion extending lengthwise thereof and a groove or dado extending from the inner edge of the sill transversely through said raised portion, in which groove water may be conducted from the inner to the outer side of the sill, and a jamb having a recess the walls of which extend the full width of the jamb to receive the end of the sill and also having a tongue formed in and extending across the jamb to enter said groove.

2. A sill having a transverse groove or dado and a rabbet adjacent said groove forming a transverse rib across the sill, and a jamb having a transverse recess to receive the end of said sill, the jamb having a rib extending from the upper wall of said recess acting as a tongue to enter said transverse groove and a shoulder to engage said rabbet, the bottom wall of said recess being seated against said sill.

3. A sill having a transverse groove or dado and a rabbet adjacent said groove forming a transverse rib, and a jamb having a transverse recess to receive the end of said sill, the upper wall of said recess having a tongue to enter said transverse groove and a shoulder to engage said rabbet, the bottom wall of said recess being seated against said sill, the lower wall of said recess having a lug or shoulder extending therefrom to engage the under surface of said sill and cooperate with the interlocking members of the jamb and the upper surface of the sill, for the purpose specified.

In witness whereof, I have hereunto set my hand this 12 day of November, 1929.

EARL C. SWANSON.
